UNITED STATES PATENT OFFICE.

JESSE G. VINCENT, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

No. 926,151.

Specification of Letters Patent.

Patented June 29, 1909.

Application filed September 9, 1907. Serial No. 391,928.

To all whom it may concern:

Be it known that I, JESSE G. VINCENT, a citizen of the United States, residing at Detroit, in the county of Wayne and State of Michigan, have invented certain new and useful Improvements in Adding-Machines, of which the following is a specification.

The present invention relates to that class of adding machines in which the mechanism is caused to operate to do the adding by the mere act of touching or depressing a selected key or keys representing the amount to be added. In other words, the keys do not merely set certain stops which regulate the extent of movement of parts when an operation is thereafter performed, as for example by the drawing forward of a handle lever, but the touching or depression of keys immediately results in a complete operation of the machine.

One object of the invention is to provide a form of mechanism which will properly respond to depression of keys under the most speedy manipulation or play of the keyboard.

Another object is to relieve the keys themselves of all work in the matter of effecting adding movements of the mechanism, so that finger pressure is not relied upon in this regard and the keyboard will have an extremely light touch which promotes speed of operation.

A further object of the invention is to provide a reliable form of transfer or carrying mechanism by which the additional increment of movement of a wheel of higher denomination can accompany movement of such wheel in response to depression of a key in its own bank.

A still further object of the invention is to provide for clearing the mechanism or setting all the number wheels at zero by the simple touch or depression of a special key.

With these and incidental objects in view the invention consists in certain novel features of construction and combinations of parts, the essential elements whereof are recited in the appended claims and a preferred form of embodiment of which is described in detail hereinafter and fully illustrated in the accompanying drawings forming a part of this specification.

Of said drawings Figure 1 represents the complete improved mechanism in right-side elevation, the inclosing casing appearing in

section as well as certain supporting shafts and a bed plate; Fig. 2 represents a partial top plan view of the machine with a portion of the casing broken away to disclose interior parts, some of which appear in horizontal section; Fig. 3 is a more extended horizontal section corresponding with that portion of Fig. 2 in which parts appear in section; Fig. 4 is a cross-section on the lines 4-4 of Fig. 3; Fig. 5 is a vertical cross-section on the lines 5-5 of Fig. 1; Fig. 6 represents a portion of the register or counter in right-side elevation with associated parts in section; Fig. 7 is a view similar to the right-hand portion of Fig. 1 but with the parts in different relation as brought about by depression of the clearing key; Fig. 8 is a view similar to Fig. 7 but taken on a section line farther to the left; and Fig. 9 represents a portion of the machine in right-side elevation with its motor attachment.

The reference numeral 2 designates a suitable inclosing casing through sight openings 3 in the front of the elevated rear portion of which the numbers may be read singly upon a series of register wheels 4. Through the sloping top of the forwardly extending portion of the casing protrude key stems 5 surmounted by suitably inscribed buttons 6, the latter being as usual numbered from 1 to 9 and in the present instance illustrated (see Fig. 2) as also inscribed with complementary numbers for use in subtraction. The key stems are arranged to slide up and down the slots of the casing top and slots of a bed plate 7 suitably supported within the casing and said key stems are normally upheld by suitable springs 8. The stems of a bank or row of keys are preferably offset alternately as shown in Figs. 3 and 4 so that they stand in staggered relation to each other on opposite sides of a horizontally arranged slide bar 9, there being one of these slide bars for each row or bank of keys. Portions of each slide bar are struck up first on one side and then on the other to form stop projections 10 to contact with the keys respectively. The sides of the key stems facing the slide bar are channeled as shown at 11 to permit the free passage of said stop projections but when any key stem is moved down by finger pressure on its button a portion of the stem is carried in front of the nearest stop projection pointing toward it. The stop pro-

jections are normally at varying distances from the key stems with which they respectively coöperate, so as to provide for the necessary differential movement of the slide bar. Thus when stopped by contact with the key stem whose button bears the numeral 9 the movement of the slide bar is nine times as far as when stopped by contact with the key stem whose button bears the numeral 1. It will be seen that the staggered arrangement of key stems and stop projections provides for a more compact assemblage with the particular advantage of shortening the row of keys. The key stems are notched as shown at 12 in sides opposite those in which the channels 11 are formed, these notches coöoperating with detent plates 13 hinged upon standards 14 which rise from the bed plate 7 and are pressed by springs 15 into engagement with the key stems. Thus when any key is depressed it is caught and held down by the engagement of the associated detent plate 13 with the notch 12. As will hereinafter be explained the slide bar is driven forward upon depression of a key and corresponding movement transmitted to the associated number wheel 4. As the slide bar when thus driven forward contacts with the depressed key stem the latter is released by the displacement of the detent plate 13. To this end the latter is formed with a rearwardly and downwardly extending finger 16 (Fig. 1) having a laterally inclined lug 17 (Fig. 3) against which the stop projection 10 acts as it approaches the depressed key stem.

Each slide bar 9 is permitted vertical vibration as well as longitudinal movement, said bar at its forward end having oppositely projecting studs 18 which normally seat in notches of uprights 19 on the bed plate 7 as shown in Fig. 1. For ease of operation the bar is mounted between a pair of grooved rollers 20 turning on cross-rods 45 supported by said uprights. At the rear each slide bar is formed as a rectangular frame, the upper side of which constitutes a rack 21 for coöperation with a gear wheel 22 for transmitting movement to the number wheel 4. Normally the rack is disengaged from the gear wheel as shown in Fig. 1 but the depression of any key in the associated bank raises the rack into mesh with the wheel. To this end a pair of bell cranks 23 embrace the slide bar carrying between them a roller 24 occupying the longitudinal slot provided by the open center of the rectangular frame-like portion of the bar. These bell cranks are pivoted upon a cross-rod 25 and their upstanding portions are jointed to a horizontally-extending strip or bar 26 which at its forward end is jointed to upstanding arms of a pair of bell cranks 28. The forwardly extending arms of the latter are normally upheld by a spring 29 which thus

tends to lower the rear end of the slide bar 9 whose weight of course also tends to keep it in lowered position. The strip or bar 26 extends adjacent the key stems and carries a stud 30 for coöperation with each stem. 70 The stems are formed with cam edges 31 so that upon depression of any key the strip or bar 26 will be moved forward by reason of the action of such cam edge upon the stud 30. Such forward movement of such strip 75 or bar necessarily swings the upright arms of the bell cranks 23 and 28 forwardly and the consequent upward swing of the rearwardly extending arms of the former raises the rack 21 into mesh with the gear wheel 22. 80

Each gear wheel 22 carries a drum 32 containing a coiled spring 33 secured to a shaft 34, which when the machine is in use constantly rotates in a direction to wind up the springs. The latter are in frictional contact at their outer ends with the interior surfaces of their respective drums 32 and with the wheels 22 unrestrained the motion of the shaft 34 will be transmitted to said wheels through the medium of said springs. 90 However, each gear wheel 22 has formed with or secured to it a ratchet wheel 35 and the ratchet wheels are normally engaged by pawls 36 pivoted upon a cross-rod 37 and connected by links 38 with the pairs of bell 95 cranks 23 respectively. So long as a rack bar is in its lowered position out of mesh with the associated gear wheel 22 the pawl remains in engagement with the ratchet wheel and prevents turning of the gear 100 wheel, the spring 33 simply slipping on the interior surface of the drum. However, it will be recalled that upon depression of a key the bell cranks 23 are vibrated. Thus the upward movement of the rearwardly extending arms of such bell cranks by elevating the forwardly extending arm of the pawl will disengage the rearwardly extending portion thereof from the ratchet wheel. When this takes place the rack 21 will have 110 been brought into mesh with the gear wheel 22 and consequently the movement of the latter is transmitted to the rack and limited by the abutment of the latter against the depressed key. It will also be remembered 115 that as the stop projection of the rack bar approaches the depressed key stem the detent of the latter is displaced and the key rises. The rise of the key permits the spring 29 to restore the bell cranks 23 to normal position and throw the pawl 36 into engagement with the ratchet wheel. Hence no movement of the gear wheel will take place except when in mesh with the rack. The latter is normally held in its rearward position by a spring 27 and upon its disengagement from the gear wheel after measuring the movement thereof said spring draws the rack bar back to its normal position. Passing now to the register or counter proper a 120 125 130

supporting shaft 40 extends from side to side of the casing and the number wheels 4 are loosely journaled thereon. These number wheels are connected with each other 5 and with the gears 22 by differential gearing. Thus each number wheel has a radial shaft 41 carrying a bevel pinion 42 and the latter meshes with a bevel gear 43 journaled on the shaft 40 and carrying a spur pinion 44 in mesh with the associated gear wheel 22. The bevel pinion 42 of the units number wheel meshes with a fixed bevel gear 45 on one of the uprights of the supporting framework as shown in Fig. 5. Each of the bevel 10 pinions 42 of the other number wheels meshes with a bevel gear 46 loosely journaled on the shaft 40 and carrying a ratchet wheel 47. It will be obvious that with the bevel gears 46 held stationary transmission of movement 15 from the other gear wheels 22 to their associated number wheels will be accomplished exactly the same as transmission of movement from the right-hand gear wheel 22 to the units number wheel. However, when the 20 units wheel has registered up to its capacity it should of course carry one to the next higher wheel and that wheel should transfer to the next and so on. This is the purpose of the differential gearing above described, 25 it being apparent that by advancing any one of the bevel gears 46 the associated number wheel will be moved farther than if said bevel gear remained stationary and that such advance of said bevel gear can take place 30 simultaneously with movement of the number wheel by its gear wheel 22.

In the present instance each number wheel is inscribed with two aligned rows of numerals from 1 to 9 with intervening zeros. 35 Consequently upon the completion of a half rotation of a number wheel it should transfer or carry 1 to the next higher wheel. The gearing above described is so proportioned and the ratchet wheels 47 so constructed that 40 the turning of any one of the latter the extent of a single tooth will advance the associated number wheel one step. Each number wheel except the one farthest to the left carries on its side next the adjacent wheel of 45 higher order a cam disk 48 having two cam rises co-acting with a roller 49 on an arm 50 pivotally supported by a cross-shaft or rod 51 and held in engagement with the cam disk by a spring 50^a. This arm 50 carries at 50 its forward end a pivoted pawl 52 pressed by a spring 53 into engagement with the ratchet wheel 47 of the next number wheel to the left. It will be seen that as the number wheel of lower order turns one of the cam 55 rises of the disk 48 will elevate the arm 50 against the stress of its spring and when the highest point of the cam rise passes the roller 49 the spring 50^a will return said arm to its lower position. The elevation of the 60 arm by the cam rise is sufficient to carry the 65 pawl 52 backwardly over one of the ratchet teeth and permit it to drop behind such tooth so that when the arm 50 lowers the ratchet wheel will be advanced and the transfer effect heretofore described thereupon 70 produced.

It is of course essential that the bevel gears 46 shall be definitely controlled and therefore precautions are taken to prevent any possible retrograde movement thereof 75 or any advance except as actuated by the pawls 52. To this end restraining pawls 54 are pivoted upon the shaft 51 and drawn by springs 55 into engagement with the ratchets 47 respectively. The engagement of these 80 pawls with the ratchets is such as to prevent any retrograde movement thereof and they are also availed of to prevent any advance of the ratchets except as actuated by the pawls 52. To this end tie-plates 56 are mounted 85 upon the shaft 40, being longitudinally slotted as shown at 57 for suitable play in the direction of the diameters of the number wheels. Each tie-plate connects a pawl 52 with a pawl 54, the lower end of the tie-plate being longitudinally slotted on a slight angle as shown at 58 to embrace a headed stud 59 on the pawl 54 and the upper end of the tie-plate being enlarged and slotted 90 in the arc of a circle as shown at 60 to embrace a headed stud 61 on the pawl 52. The slot 60 provides for the reciprocation of the pawl 52 required to actuate the ratchet 41 and the slots 57 and 58 provide for movement of the tie-plate with said pawl 52 as 95 the latter rises in riding over the backs of the ratchet teeth but this movement of the tie-plate results in locking the pawl 54 to the ratchet wheel. Of course forward turning of the ratchet wheel cannot take place 100 unless the pawl 54 is free to move downwardly and it can move downwardly far enough to permit a tooth of the ratchet wheel to pass it, only when the tie-plate 56 is in its lowered position permitting the stud 59 to 105 move the length of the slot 58. When the pawl 52 drops in behind a ratchet tooth the tie-plate returns to its normal position and then as the pawl 52 advances the pawl 54 retreats and permits the ratchet tooth against 110 which it is bearing to pass by.

Passing now to the means for turning the register or counter to zero a special key is provided in the form of a lever 70 preferably located at the right-hand side of the machine as shown in Fig. 2 and secured to a shaft 71 extending across the machine and equipped with a series of upstanding arms 72, one for each of the strips or bars 26 and adapted when the key is depressed and the 115 shaft rocked to thrust said strips or bars forwardly the same as though they were acted upon by depression of amount keys. This of course has the effect of moving the racks 21 into mesh with their respective gear 120

65 130

wheels 22. Now the right-hand units number wheel may be moved directly to zero position but this would not do with reference to the other number wheels because the inevitable transfer movements would carry such wheels beyond and they would not be left at zero. Consequently the depression of the special key, while directly resulting in advance of the units wheel to zero position, 10 limits advance of the other wheels to positions where they would exhibit a row of 9s so far as transmission of movement by their gear wheels 22 is concerned. But the advance of the units wheel to zero of course 15 results in carrying one to the 10s wheel so that the latter will move on to zero position and in so doing cause the carrying of one to the next wheel and so on. For the purpose of properly limiting the zero-setting 20 movements of the number wheels as directly produced by their respective gear wheels 22, the shaft 71 has secured to it a series of stop arms, one for each number wheel, the right-hand arm 75 being slightly longer than the 25 other arms 76 so that its hooked rear end 77, projected in the path of a stud 78 on the units wheel, will permit advance of the latter to the zero position. The hooked rear ends 79 of the shorter arm 76 when projected in the paths of similar studs on the 30 other number wheels limits their movement to one step short of zero position. The arms 75 and 76 are of course normally lowered so that the hooks 77 and 79 are entirely out of 35 the paths of studs 78. The depression of the key 70 in rocking the shaft 71 lifts the arms 75 and 76 to the positions shown in Figs. 7 and 8 where their hooked rear ends are represented as abutments for the stud 78 to 40 counter.

It may happen that the units wheel is already standing at zero when the clearing key is depressed. In such case there would of course be no movement of said wheel and 45 consequently the usual transfer operation resulting from movement of that wheel to zero would not take place. To provide against such a contingency the transfer pawl 50 associated with this particular wheel is connected by a link 80 with a crank arm 81 secured to the shaft 71. Through these connections the transfer pawl will be caused to operate by the act of depressing the clearing key, the same as though the units wheel had 55 advanced to the zero position instead of already standing at that position.

It will of course be understood that the clearing key must be released in order to permit the transfer movements of the wheels 60 to take place, such movements occurring when the gear wheels 22 are locked as well as when the same are unlocked.

Continuous rotation of the shaft 34 may be produced in any suitable manner. In 65 the present instance a worm-wheel 82 is

shown rotatively connected with said shaft and engaged by a worm 83 (Fig. 9) on a shaft 84 geared to an electric motor 85, the latter having a suitable on-and-off switch 86. Such a motor can conveniently be located in rear of the casing 2 as shown in Fig. 9.

What is claimed is:

1. In a machine of the character described, the combination of a register wheel, a continuously rotating shaft, means interposed between the same and the register wheel constantly tending to advance the latter but normally restrained from so doing, said means including an element deriving motion 75 directly from the shaft and keys for removing such restraint and variously limiting the resultant advance of the said element.

2. In a machine of the character described, the combination of a register wheel, a gear 85 engaged therewith, a continuously rotating shaft, a spring tensioned by said shaft and tending to advance said register wheel but normally restrained from so doing, and 90 keys for removing such restraint and variously limiting the resultant advance of the register wheel.

3. In a machine of the character described, the combination of a register wheel, a continuously rotating shaft, a gear loosely 95 mounted thereon, a spring connected with the shaft and frictionally engaged with the said gear, means normally restraining the latter, and keys for disabling said means and variously limiting the resultant 100 advance of the register wheel.

4. In a machine of the character described, the combination of a register wheel, a gear engaged therewith, a continuously rotating shaft, a spring tensioned by said shaft and tending to advance said register wheel, means normally restraining said gear, a 105 rack bar normally disengaged from the gear, and keys adapted to disable said restraining means, engage the rack bar with the gear and variously limit the resultant movement of said rack bar, the gear and the register wheel.

5. In a machine of the character described, the combination of a register wheel, a continuously rotating shaft, a gear loosely mounted thereon, a spring connected with the shaft and frictionally engaged with the said gear, means normally restraining the latter, a rack bar normally disengaged from the gear, and keys adapted to disable said restraining means, engage the rack bar with the gear, and variously limit the resultant movement of said rack bar, the gear and the register wheel.

6. In a machine of the character described, the combination of a register wheel, a gear engaged therewith, a continuously rotating shaft, a spring tensioned by said shaft and tending to advance said register wheel,

- means normally restraining said gear, a rack bar normally disengaged from the gear, depressible keys adapted to disable said restraining means, engage the rack bar 5 with the gear and variously limit the resultant movement of said rack bar, the gear and the register wheel, and detents for temporarily holding the keys depressed, with provisions for disabling any detent by 10 the rack bar.
7. In a machine of the character described, the combination of a register wheel, a continuously rotating shaft, a gear loosely mounted thereon, a spring connected with 15 the shaft and frictionally engaged with the said gear, means normally restraining the latter, a rack bar normally disengaged from the gear, depressible keys adapted to disable said restraining means, engage the rack bar 20 with the gear and variously limit the resultant movement of said rack bar, the gear and the register wheel, and detents for temporarily holding the keys depressed, with provisions for disabling any detent by 25 the rack bar.
8. In a machine of the character described, the combination of a register wheel, a gear engaged therewith, a continuously rotating shaft, a spring tensioned by said shaft and 30 tending to advance said register wheel, means normally restraining said gear, a rack bar normally disengaged from the gear, depressible keys adapted to disable said restraining means, engage the rack bar 35 with the gear and variously limit the resultant movement of said rack bar, the gear and the register wheel, detents for temporarily holding the keys depressed, with provisions for disabling any detent by the rack 40 bar, and means for restoring the rack bar to normal after disengagement from the gear by the restoration of the depressed key.
9. In a machine of the character described, the combination of a register wheel, a continuously rotating shaft, a gear loosely 45 mounted thereon, a spring connected with the shaft and frictionally engaged with the said gear, means normally restraining the latter, a rack bar normally disengaged from the gear, depressible keys adapted to disable 50 said restraining means, engage the rack bar with the gear and variously limit the resultant movement of said rack bar, the gear and the register wheel, detents for temporarily holding the keys depressed, with provisions for disabling any detent by the rack bar, and means for restoring the rack bar to 55 normal after disengagement from the gear by the restoration of the depressed key.
10. In a machine of the character described, the combination of a register wheel, a gear engaged therewith, a continuously rotating shaft, a spring tensioned by said shaft and tending to advance said register wheel, 60 means normally restraining said gear, a rack 65 bar normally disengaged from the gear, depressible spring-upheld keys adapted to disable said restraining means, engage the rack bar with the gear and variously limit the resultant movement of said rack bar, the gear and the register wheel, and detents for temporarily holding the keys depressed, with provisions for disabling any detent by the rack bar.
11. In a machine of the character described, the combination of a register wheel, a continuously rotating shaft, a gear loosely mounted thereon, a spring connected with the shaft and frictionally engaged with the said gear, means normally restraining the latter, a rack bar normally disengaged from the gear, depressible keys adapted to disable said restraining means, engage the rack bar with the gear and variously limit the resultant movement of said rack bar, the gear and the register wheel, and detents for temporarily holding the keys depressed, with provisions for disabling any detent by the rack bar.
12. In a machine of the character described, the combination of a register wheel, a gear engaged therewith, a continuously rotating shaft, a spring tensioned by said shaft and tending to advance said register wheel, means normally restraining said gear, a rack bar normally disengaged from the gear, depressible keys adapted to disable said restraining means, engage the rack bar with the gear and variously limit the resultant movement of said rack bar, the gear and the register wheel, and detents for temporarily holding the keys depressed, with provisions for disabling any detent by the rack bar.
13. In a machine of the character described, the combination of a register wheel, a continuously rotating shaft, a gear loosely mounted thereon, a spring connected with the shaft and frictionally engaged with the said gear, means normally restraining the latter, a rack bar normally disengaged from the gear, depressible keys adapted to disable said restraining means, engage the rack bar with the gear and variously limit the resultant movement of said rack bar, the gear and the register wheel, and detents for temporarily holding the keys depressed, with provisions for disabling any detent by the rack bar.
14. In a machine of the character described, the combination of a register wheel, a gear engaged therewith, a continuously rotating shaft, a spring tensioned by said shaft and tending to advance said register wheel, means normally restraining said gear, a rack bar normally disengaged from the gear, depressible keys adapted to disable said restraining means, engage the rack bar with the gear and variously limit the resultant movement of said rack bar, the gear and the register wheel, and detents for temporarily holding the keys depressed, with provisions for disabling any detent by the rack bar.

gear, a rack bar normally disengaged from the gear, depressible keys adapted to disable said restraining means, engage the rack bar with the gear and variously limit the resultant movement of said rack bar, the gear and the register wheel, detents for temporarily holding the keys depressed, with provisions for disabling any detent by the rack bar, and a spring for restoring the rack bar to normal after disengagement from the gear by the restoration of the depressed key.

15. In a machine of the character described, the combination of a register wheel, a gear engaged therewith, a continuously ro-

15 tating shaft, a spring tensioned by said shaft and tending to advance said register wheel, means normally restraining said gear, a rack bar normally disengaged from the gear, compressible spring-upheld keys adapt-

20 ed to disable said restraining means, engage the rack bar with the gear and variously limit the resultant movement of said rack bar, the gear and the register wheel, detents for temporarily holding the keys depressed,

25 with provisions for disabling any detent by the rack bar, and a spring for restoring the rack bar to normal after disengagement from the gear by the restoration of the depressed key.

30 16. In a machine of the character described, the combination of a register wheel, a continuously rotating shaft, a gear loosely mounted thereon, a spring connected with the shaft and frictionally engaged with the
35 said gear, means normally restraining the latter, a rack bar normally disengaged from the gear, depressible spring-upheld keys adapted to disable said restraining means, engage the rack bar with the gear and va-

40 riously limit the resultant movement of said rack bar, the gear and the register wheel, detents for temporarily holding the keys depressed, with provisions for disabling any detent by the rack bar, and a spring for re-
45 storing the rack bar to normal after disengagement from the gear by the restoration of the depressed key.

17. In a machine of the character described, the combination of a register wheel, 50 a gear engaged therewith, a continuously rotating shaft, a spring tensioned by said shaft and tending to advance said register wheel, a ratchet on the latter, a pawl normally engaging said ratchet to restrain the spring, 55 and keys for displacing the pawl and variously limiting the resultant advance of the register wheel.

18. In a machine of the character described, the combination of a register wheel, a continuously rotating shaft, a gear loosely mounted thereon, a spring connected with the shaft and frictionally engaged with the said gear, a ratchet on the latter, a pawl normally engaging said ratchet to restrain the spring, and keys for displacing the pawl.

and variously limiting the resultant advance of the register wheel.

19. In a machine of the character described, the combination of a register wheel, a gear engaged therewith, a continuously rotating shaft, a spring tensioned by said shaft and tending to advance said register wheel, a ratchet on the latter, a pawl normally engaging said ratchet to restrain the spring, a rack bar normally disengaged from the gear, and keys adapted to displace said pawl, engage the rack bar with the gear and variously limit the resultant advance of the register wheel. 70 75

20. In a machine of the character described, the combination of a register wheel, a continuously rotating shaft, a gear loosely mounted thereon, a spring connected with the shaft and frictionally engaged with the said gear, a ratchet on the latter, a pawl normally engaging said ratchet to restrain the spring, a rack bar normally disengaged from the gear, and keys adapted to displace said pawl, engage the rack bar with the gear and variously limit the resultant advance of the register wheel. 80 85 90

21. In a machine of the character described, the combination of a register wheel, a gear engaged therewith, a continuously rotating shaft, a spring tensioned by said shaft 95 and tending to advance said register wheel, a ratchet on the latter, a pawl normally engaging said ratchet to restrain the spring, depressible keys for displacing the pawl and variously limiting the resultant advance of the register wheel and detents for temporarily holding the keys depressed, with provisions for disabling any detent by the rack 100 bar.

22. In a machine of the character described, the combination of a register wheel, a continuously rotating shaft, a gear loosely mounted thereon, a spring connected with the shaft and frictionally engaged with the said gear, a ratchet on the latter, a pawl normally engaging said ratchet to restrain the spring, depressible keys for displacing the pawl and variously limiting the resultant advance of the register wheel, and detents for temporarily holding the keys depressed, with provisions for disabling any detent by the rack bar. 105
110
115

23. In a machine of the character described, the combination of a register wheel, a gear engaged therewith, a continuously rotating shaft, a spring tensioned by said shaft and tending to advance said register wheel, a ratchet on the latter, a pawl normally engaging said ratchet to restrain the spring, a rack bar normally disengaged from the gear, depressible keys adapted to displace said pawl, engage the rack bar with the gear and variously limit the resultant advance of the register wheel, and detents for temporarily holding the keys depressed, with pro- 130

visions for disabling any detent by the rack bar.

24. In a machine of the character described, the combination of a register wheel, a continuously rotating shaft, a gear loosely mounted thereon, a spring connected with the shaft and frictionally engaged with the said gear, a ratchet on the latter, a pawl normally engaging said ratchet to restrain the spring, a rack bar normally disengaged from the gear, depressible keys adapted to displace said pawl, engage the rack bar with the gear and variously limit the resultant advance of the register wheel, and detents for temporarily holding the keys depressed, with provisions for disabling any detent by the rack bar.

25. In a machine of the character described, the combination of a register wheel, a gear engaged therewith, a continuously rotating shaft, a spring tensioned by said shaft and tending to advance said register wheel, a ratchet on the latter, a pawl normally engaging said ratchet to restrain the spring, depressible keys for displacing the pawl and variously limiting the resultant advance of the register wheel, detents for temporarily holding the keys depressed, with provisions for disabling any detent by the rack bar, and means for restoring the rack bar to normal after disengagement from the gear by the restoration of the depressed key.

26. In a machine of the character described, the combination of a register wheel, a continuously rotating shaft, a gear loosely mounted thereon, a spring connected with the shaft and frictionally engaged with the said gear, a ratchet on the latter, a pawl normally engaging said ratchet to restrain the spring, depressible keys for displacing the pawl and variously limiting the resultant advance of the register wheel, detents for temporarily holding the keys depressed, with provisions for disabling any detent by the rack bar, and means for restoring the rack bar to normal after disengagement from the gear by the restoration of the depressed key.

27. In a machine of the character described, the combination of a register wheel, a gear engaged therewith, a continuously rotating shaft, a spring tensioned by said shaft and tending to advance said register wheel, a ratchet on the latter, a pawl normally engaging said ratchet to restrain the spring, a rack bar normally disengaged from the gear, depressible keys adapted to displace said pawl, engage the rack bar with the gear and variously limit the resultant advance of the register wheel, detents for temporarily holding the keys depressed, with provisions for disabling any detent by the rack bar, and means for restoring the rack bar to normal after disengagement

from the gear by the restoration of the depressed key.

28. In a machine of the character described, the combination of a register wheel, a continuously rotating shaft, a gear loosely mounted thereon, a spring connected with the shaft and frictionally engaged with the said gear, a ratchet on the latter, a pawl normally engaging said ratchet to restrain the spring, a rack bar normally disengaged from the gear, depressible keys adapted to displace said pawl, engage the rack bar with the gear and variously limit the resultant advance of the register wheel, detents for temporarily holding the keys depressed, with provisions for disabling any detent by the rack bar, and means for restoring the rack bar to normal after disengagement from the gear by the restoration of the depressed key.

29. In a machine of the character described, the combination of a register wheel, a gear engaged therewith, a continuously rotating shaft, a spring tensioned by said shaft and tending to advance said register wheel, means normally restraining said gear, a rack bar normally disengaged from the gear, a bell crank lever connected with said rack bar, a longitudinally movable strip or bar connected with said bell crank lever, and a series of depressible keys adapted to move said strip or bar and thereby engage the rack with the gear, said keys adapted to disable said restraining means and variously limit the resultant movement of the rack bar, the gear and the register wheel.

30. In a machine of the character described, the combination of a register wheel, a gear engaged therewith, a continuously rotating shaft, a spring tensioned by said shaft and tending to advance said register wheel, means normally restraining said gear, a rack bar normally disengaged from the gear, a bell crank lever connected with said rack bar, a longitudinally movable strip or bar connected with said bell crank lever and equipped with studs, and a series of depressible keys having cam-portions for engaging said studs to move said strip or bar and thereby engage the rack with the gear, said keys adapted to disable said restraining means and variously limit the resultant movement of the rack bar, the gear and the register wheel.

31. In a machine of the character described, the combination of a register wheel, a gear engaged therewith, a continuously rotating shaft, a spring tensioned by said shaft and tending to advance said register wheel, a ratchet on the latter, a pawl normally engaging said ratchet to restrain the spring, a bell crank lever connected with said rack bar, a longitudinally movable strip or bar connected with said bell crank lever, a

series of depressible keys adapted to move said strip or bar and thereby engage the rack with the gear, said keys adapted to variously limit the movement of the rack 5 bar, and an operating connection between said bell crank lever and the pawl whereby the latter is displaced when a key is depressed.

32. In a machine of the character described, the combination of a register or counter, a continuously rotating shaft, means interposed between the same and the register constantly tending to advance the latter but normally restrained from so doing, 10 a longitudinally movable bar adapted to be engaged with and disengaged from said means, and having a series of stop projections, depressible keys for removing the restraint to operation of said means and engaging said bar therewith, said keys extending in a series adjacent said bar and adapted when depressed to present abutments to the stop projections thereof, and detents for said keys to temporarily hold them down, with 15 provisions for displacement of the detents by the stop projections.

33. In a machine of the character described, the combination of a register or counter, a continuously rotating shaft, 20 means interposed between the same and the register constantly tending to advance the latter but normally restrained from so doing, a longitudinally movable bar adapted to be engaged with and disengaged from said means, and having a series of stop projections, depressible keys for removing the restraint to operation of said means and engaging said bar therewith, said keys extending in a series adjacent said bar and adapted 25 when depressed to present abutments to the stop projections thereof, and detents for said keys to temporarily hold them down, said detents having cam lugs against which the stop projections act to displace the detents.

40 34. In a machine of the character described, the combination of register wheels carrying planet gears, a series of pairs of gears engaged respectively therewith, key-controlled means for operating corresponding gears of said pairs, ratchets on the other gears of said pairs, pawls spring-drawn to advance said ratchets, cams on lower denomination register wheels to retract said pawls, restraining pawls engaging said 45 ratchets, and tie-plates connecting the actuating pawls and the restraining pawls, slotted to permit displacement of the latter during actuation of wheels by the former but prevent advance of the ratchets independently of the pawls.

35. In a machine of the character described, the combination of register wheels, transfer mechanism, means constantly tending to individually advance said wheels but 50 normally restrained, keys for removing such

restraint and variously limiting the resultant advance of the wheels, and means for removing the restraint independently of the keys and setting a zero stop for the lowest register wheel and stops for the other wheels 70 to limit their advance to a step short of the zero position.

36. In a machine of the character described, the combination of register wheels, transfer mechanism, means constantly tending to individually advance said wheels but normally restrained, keys for removing such restraint and variously limiting the resultant advance of the wheels, and means for removing the restraint independently of the keys and setting a zero stop for the lowest register wheel and stops for the other wheels 75 to limit their advance to a step short of the zero position, with provisions for advancing the next to the lowest wheel one step without requiring precedent movement of the lowest wheel.

37. In a machine of the character described, the combination of a series of denominational register wheels having zero positioning stop projections, transfer devices for automatically advancing one step at a time a wheel of higher denomination upon the next lower wheel advancing to zero position, means constantly tending to individually advance said wheels but normally restrained, keys for removing such restraint and variously limiting the resultant advance of the wheels, and means for removing the restraint independently of the keys and interposing 90 obstructions in the paths of the said stop projections on the wheels, the lowest wheel being permitted to advance to the zero position while higher wheels are limited to a 95 step short of zero position.

38. In a machine of the character described, the combination of a series of denominational register wheels having zero positioning stop projections, transfer devices for automatically advancing one step at a time a wheel of higher denomination upon the next lower wheel advancing to zero position, means constantly tending to individually advance said wheels but normally restrained, keys for removing such restraint and variously limiting the resultant advance of the wheels, and a manipulative rock shaft equipped to remove the restraint independently of the keys, and having arms to enter the paths of the said stop projections on 100 the wheels, the lowest wheel being permitted to advance to the zero position while higher wheels are limited to a step short of zero position.

39. In a machine of the character described, the combination of a series of denominational register wheels having zero positioning stop projections, transfer devices for automatically advancing one step at a time a wheel of higher denomination upon 115

125

130

the next lower wheel advancing to zero position, means constantly tending to individually advance said wheels but normally restrained, keys for removing such restraint 5 and variously limiting the resultant advance of the wheels, a manipulative rock shaft equipped to remove the restraint independently of the keys, and having arms to enter the paths of the said stop projections on the 10 wheels, the lowest wheel being permitted to advance to the zero position while higher wheels are limited to a step short of zero position, and connections between said rock shaft and the transfer devices associated 15 with the lowest wheel, for effecting the one-step advance of the next higher wheel without precedent advance of said lowest wheel.

40. In a machine of the character described, the combination of a series of 20 denominational register wheels having zero positioning stop projections, transfer devices for automatically advancing one step at a time a wheel of higher denomination upon the next lower wheel advancing to zero position, gears for individually advancing said 25 wheels, springs tending to turn said gears, a continuously rotating shaft tensioning said springs, ratchets carried by said gears, pawls engaging said ratchets, racks normally disengaged from 30 the gears, longitudinally movable bars operatively connected with said racks and said pawls, rows of depressible keys for moving said bars and thereby displacing the pawls and engaging the racks with the gears, said 35 keys adapted to variously limit the resultant advance of the racks, a manipulative rock shaft having projections engaging said bars and arms for interposition in the paths of the stop projections on the wheels to hold 40 the lowest wheel at zero and the others one step short of zero, and a link cranked to said rock shaft and connected with the pawl of the transfer devices associated with the lowest wheel, for effecting the one-step 45 advance of the next higher wheel without precedent advance of said lowest wheel.
